UNITED STATES PATENT OFFICE

FRANK MAXANT, OF AYER, MASSACHUSETTS

RAILWAY-CAR JOURNAL BOX

Application filed June 17, 1927. Serial No. 199,524.

This invention relates to axle boxes for railway cars, the boxes containing roller bearings.

The object of the invention is to produce such a bearing in a form which will limit frictional resistance to rotation of the axle and which is composed of parts which are convenient for assembling and separating and which maintain their positions effectively when assembled.

In the accompanying drawings,

Fig. 1 is an upright section along the axial line of the structure on the line, 1—1, of Figs. 2 and 7, looking toward the left;

Fig. 1a is an enlarged detail from a part of Fig. 1;

Fig. 2 is an elevation of the outer end of the structure;

Fig. 3 is a section similar to Fig. 1, the axle box and the part of the axle being omitted, whereby the interior of the housing is shown;

Fig. 4 is a side elevation of the housing shown by Fig. 3;

Fig. 5 is an upright cross section on the line, 5—5, of Fig. 3, looking in the direction of the arrow;

Fig. 6 is an upright cross section on the line, 6—6, of Fig. 1, looking toward the left;

Fig. 7 is a sectional end elevation of the structure shown in Fig. 1, the end wall and the cap and the outer ring and the outer cage ring having been removed;

Fig. 8 is an upright section on the line, 8—8, of Fig. 7, looking toward the right and showing the rocking engagement between the axle box and the housing at one side of the structure;

Fig. 9 is a section on the line, 9—9 of Figs. 1 and 7, looking toward the left;

Fig. 10 is a horizontal section on the line, 10—10, of Figs. 1, 2 and 7;

Fig. 11 is an end elevation of the binding cap shown in Figs. 1 and 14;

Fig. 12 is a cross section on the line, 12—12, of Fig. 1, looking toward the left;

Fig. 13 is a cross section on the line, 13—13, of Fig. 12;

Fig. 14 is a sectional elevation showing the

mechanism applied to the journal sleeve for drawing said sleeve from the journal.

Referring to the drawings, A is a part of the axle, A1 is a shoulder on the axle. A2 is the journal. This is tapering as shown by the drawings. A3 is a socket formed in the end of the journal on the axial line of the journal. A4 is a bolt having one end threaded in said socket and having its outer end threaded to receive the nut, A5. B is a bronze ring surrounding the journal and resting against the shoulder, A1. B1 is an oil-hardened sleeve tapered inside to fit the tapering face of the journal. The exterior of the sleeve is cylindrical. The inner end of this sleeve meets the ring, B. Dowels, B2, extend horizontally into the sleeve and the ring at their meeting faces. The outer end of the sleeve has a transverse face. At the outer edge of said face the sleeve is provided with a circumferential channel, B4. B3, B3, are two threaded sockets formed horizontally in the transverse face of the sleeve diametrically opposite each other and equidistant from the axial line of the journal. The purpose of these sockets will be explained further on. An outer retaining ring, B5, loosely surrounds the end of the journal and is seated against the outer end of the sleeve B1, and has a flange, B6, extending into the channel, B4. Thus engagement is made for holding this ring against movement transverse to the journal.

This ring, B5, is held in position by a cap, B7, which loosely surrounds the bolt, A4. The nut, A5, is turned to make it bear against said cap. This cap has two horizontal holes, B8, in alignment with the sockets B3. The function of these holes will be described further on.

An inner cage ring, C, is placed next to the bronze ring, B. An outer cage ring, C1, is placed adjacent the inner face of the outer ring, B5. These rings are joined by three horizontal cage rods, C2. Between the cage rings are horizontal rollers, C3, having journals, C4, resting in bearings, C5, formed in the cage rings. These journals are to extend through the cage rings so as to adapt the inner journals to bear against the ring, B,

and so as to adapt the outer journals to bear against the outer ring, B5, the cage rings being free from the rings, B and B5, and the sleeve, B1. Thus binding of the cage rings against the rings, B and B5, and the sleeve, B1, is avoided and the entire cage is made free for rotation around the sleeve, B1.

An outer sleeve or lining, D, surrounds the entire cage and bears against the rollers, C3, and has its outer end even with the outer ends of the rollers, C3, and has its inner end reaching almost even with the inner ends of the rollers.

The axle box body, E, surrounds and fits closely to the sleeve, D, whereby said sleeve is held immovably in said body. The outer end of the body, E, is even with the outer end of the sleeve, D. The inner end of the body, E, has a flange, E1, directed toward the journal and reaching almost to the inner cage ring, C. Diametrically opposite each other the flange, E1, has a notch, E1a, through which the sleeve, D, may be engaged for driving it out of the axle box body. On the upper and the lower parts of the body, E, a flanged retaining plate, E2, overlaps the outer edge of said body and partially overlaps the adjacent end of the sleeve, D, and is secured to the body, E, by means of a horizontal binding bolt, E3, extending through the plate E2, into the body, E. These two retaining plates prevent the sleeve, D, from moving outward in the body, E.

The parts above described as surrounding the journal, A2, constitute the axle box for the journal. The axle box housing will now be described.

The housing, F, surrounds the axle box and is supported thereon. The drawings show the housing of U-shape cross section, the upper part being horizontal. The axial line of the housing is shown a little below the axial line of the journal, A2. At its inner end the housing has a wall, F1, extending to the axle sleeve, A7. At its front end, the housing has an outward-directed flange, F2. In the upper part of said flange is a dowel socket, F3, extending horizontally through the outer face of said flange. An outer end wall, F4, extends across the outer end of the housing and overlaps the flange, F2. A dowel, F6, extends through the wall, F4, and into the socket, F3. Binding bolts, F5, extend horizontally through the wall, F4, into the flange, F2, for immovably securing said wall to the body of the housing. On the axial line of the journal, A2, the wall, F4, has a lubricant port, F7, which is closed by means of a screw-threaded plug, F7a. At the lower part of the wall, F4, is a lubricant drain port, F8, which may be closed by a plug, F8a.

Within the housing and at opposite sides of the axle box, the housing has an upright bearing face, F9, which is to engage the adjacent side of the axle box. Above each face,

F9, a saddle member, F10, is formed integral with the body of the housing, this member having a face which is horizontal in a transverse direction and is curved on a radius which rises from a line which is horizontal and cuts and is perpendicular to the axial line of the journal, A2. At the forward part of the saddle, F10, is a downward-directed abutment face, F11, which is approximately radial to the above-mentioned transverse horizontal line.

At each side of the axle box is a shoulder, E4, meeting and approximately conforming to the under face of the saddle member, F10. At its forward end this shoulder has an abutting face, E5, adapted to bear against the saddle abutment, F11. The housing is supported on the two shoulders, E4, by means of the saddles, F10, resting rockably on said shoulders. Outward movement of the axle box in the housing is limited by the abutment, F11. The curvature of the saddles, F10, and the shoulders, E4, allows rocking of the housing on the axle box. The faces, F9, on the housing permit such rocking but hold the axle box against sidewise movement.

When the axle, A, and the journal, A2, and the sleeve, B1, turn, contact between the sleeve, B1, and the rollers, C3, causes turning of said rollers, their journals, C4, turning in the bearings, C5. Thus the entire roller cage turns around the sleeve, B1. Lubricant introduced through the port, F7, may accumulate in the lower part of the housing and rise almost to the height of the flange, F1, below the axle. Thus the lower part of the roller cage will extend into the lubricant, all the rollers, while traversing their orbit, successively extending into the lubricant and carrying lubricant upward to reach the sleeve, B1, and the bearings, C5, of the roller journals, C4.

The upper wall of the housing is approximately horizontal. On said wall are two ribs, F13, in planes to which the journal axis is perpendicular. Said ribs are spaced from each other as shown in Fig. 3. A key rib, F14, rises from said upper wall and extends from one rib, F13, to the other perpendicular to said ribs. At each side of the housing there are two upright side ribs, F15, having their opposing faces in the same planes as are the opposing faces of the ribs, F13. These ribs, F13, F14 and F15, are for the purpose of obtaining seating for a saddle-like structure on the car truck, as is already known in the railway car art.

I claim as my invention:

1. In a structure of the kind described, the combination with an axle, of a sleeve fitted around the axle and having threaded sockets in its outer end, a cap having holes in alignment with said sockets, a bolt extending loosely through said cap and seated in the

end of the axle and screw threaded on the part extending through the cap, and a nut adapted to be threaded on said bolt on either side of said cap, and said sockets and the holes in the cap being adapted to receive bolts extending through said holes and threaded in said sockets.

2. In a structure of the kind described, the combination with an axle having a journal, 10 of a sleeve surrounding the journal, an inner cage ring, an outer cage ring, rollers between said cage rings, an outer retaining ring surrounding the outer part of the journal and extending across the outer end of 15 said sleeve and said retaining ring and said sleeve being formed for inter-engagement to prevent movement of said retaining ring transversely to said sleeve, a cap spaced from the outer end of the journal and bearing 20 against the outer face of the retaining ring, and means engaging the cap and the journal for drawing the cap toward the journal.

3. In a structure of the kind described, the combination with an axle, of a sleeve fitted 25 around the axle and having threaded sockets in its outer end, a retaining ring surrounding the axle and resting against the outer end of said sleeve, a cap having holes in alignment with said sockets, a bolt extending loosely 30 through said cap and seated in the end of the axle and screw threaded on the part extending through the cap, and a nut adapted to be threaded on said bolt on either side of the cap and said sockets and the holes in the 35 cap being adapted to receive bolts extending through said holes and threaded in said sockets after the removal of the retaining ring.

4. In a structure of the kind described, the combination of a journal, a roller cage and 40 rollers surrounding the journal for travel around the journal, an axle box surrounding the roller cage and supported on the rollers, a housing surrounding and resting on the axle box body and having at its inner end a 45 flange directed toward and surrounding the axle and said housing having at its lower part a drain port and having an outer end wall provided with a lubricant port above the lower part of said cage, whereby said housing 50 may hold a body of lubricant reaching into the orbital path of said rollers and said lubricant may be drained from the housing.

In testimony whereof I have signed my name, this 15th day of June, in the year one 55 thousand nine hundred and twenty-seven.

FRANK MAXANT.
